UNITED STATES PATENT OFFICE.

ARTHUR J. BENNETT, OF CAMBRIDGE, OHIO.

DESIGN FOR A FLOWER-HOLDING INSERT FOR VASES.

Application filed March 12, 1924. Serial No. 8,910. Term of patent 14 years.

To all whom it may concern:

Be it known that I, ARTHUR J. BENNETT, a citizen of the United States, residing at Cambridge, in the county of Guernsey and State of Ohio, have invented a new, original, and ornamental Design for Flower-Holding Insert for Vases, of which the following is a specification, reference being had to the accompanying drawings, forming part thereof.

Figure 1, is a side elevation showing my new design of flower holding insert for vases, and

I claim:

The ornamental design for a flower holding insert for vases, as shown.

ARTHUR J. BENNETT.
